SILO

Filed Nov. 26, 1928

UNITED STATES PATENT OFFICE

JAMES RUSSEL ROBERTS, OF LINCOLN, NEBRASKA

SILO

Application filed November 26, 1928. Serial No. 321,962.

My invention relates to silos and similar storage receptacles and especially to storage receptacles such as are used on the farm.

One object of my invention is the provision 5 of a silo or other storage receptacle which is wholly unaffected by the shrinkage and the expansion of the wood forming its walls.

Another object of my invention is the provision of a structure which cannot be blown 10 over when the silo is either filled or empty.

It is also my object to provide a very efficient permanent silo which can be built at a relatively low cost.

Having in view these objects and others 15 which will be pointed out in the following description, I will now refer to the drawings, in which

Figure 1 is a view in vertical section through the silo and through its anchor or retaining wall.

Figure 2 is a transverse section through a portion of two planks showing particularly the joint between the planks and showing also the concrete retaining wall and the lining between the planks and the concrete retaining wall.

Figure 3 is a transverse sectional view showing the manner in which the planks are secured to the hoops.

Figure 4 is a fragmentary enlarged horizontal section taken through a portion of the side wall of the silo.

The silo consists of a plurality of vertically positioned planks 10 in polygonal or circular form and bound together by means of hoops 11 and anchored to a concrete retaining wall 12. The planks 10 are beveled on their inner sides at their edges as shown in Figures 2 and 3 so as to form V shaped notches at the joints. These notches are closed by means of strips 13 in wedge form which are secured in place by bolts 13¹ or other suitable means. Some of the hoops 11 are made of channel iron or other material with flat surfaces contiguous to the planks 10. Each plank is individually secured to each hoop by any suitable fastening means such as a bolt 14 and nut, the nut being preferably on the outside. At its lower extremity 50 the silo wall is surrounded by a concrete re-

taining wall to which the silo is secured by means of bolts 15. The silo wall is preferably separated from the concrete retaining wall by means of one or more layers 16 of building or tar paper or the like.

The method of erecting the silo may be varied but in my preferred construction an excavation is first made and the silo is erected with its bottom resting on the surface of the soil in the excavation. The outer surface of the lower end portion of the silo is then covered with roofing paper or any suitable similar material and the bolts 15 are inserted through the roofing paper and through the planks 10. Each plank is provided with one or more bolts 15 and the bolts are so inserted that the bolt heads will be on the outside and at some distance from the planks. The concrete wall 12 is then formed by pouring concrete into the excavation around the silo wall, 70 the building or roofing paper preventing the concrete from adhering to the wood of the planks 10. After the concrete has set, the nuts may be tightened on the bolts 15 on the inner side of the silo wall and the strips 13 75 may be secured in place. In the initial assembling of the planks 10 spaces are left at the joints to allow for the expansion of the wood when it absorbs moisture either from the silage or from the atmosphere. The 80 planks 10 may be beveled at any suitable angle but the angle of the wedge block should correspond with the angle of the bevel.

It will be readily apparent that the pressure of the silage against the wedge strips 13 85 will force them into the notches at the joints between the planks 10. Plastic cement may be used back of the strips to hermetically seal the joints. At the same time the planks 10 will absorb moisture from the silage and 90 they will thus swell and close the gaps between them. In the storage of silage or other wet product the swelling of the wood will close the joints so tightly that no air or water will creep past the wedge strips and through the 95 joints. When the silo is empty, the conditions are just reversed and a rapid shrinking of the wood takes place specially in the summer weather during which the silo is empty. Each joint then presents a large open gap and 100

the wedge strips also will be found to be spaced away from the walls of the notches since there is no pressure back of them to seat them tightly in the notches. Each plank, however, is individually anchored to each hoop and to the concrete retaining wall so that even though there are large gaps at the joints, the silo as a whole will retain its form. In the prior silos when empty, the wood staves shrink and the hoops become loosened. The silo then can be twisted or tipped over easily by the wind, for the rigidity of the plank is not used to help make the silo stand in a vertical position. In order to blow my silo over, the planks would have to be broken off by the wind. The channel irons bind them all together, which makes them have the effect of bracing each other. The silo built as above described will stand more wind pressure than any other buildings on the farm whereas prior built stave silos have a great tendency to blow down. When once built, the silo will shrink or swell but it has no effect on the silo and there are no hoops to tighten after the shrinking of the silo.

The silo as above described is admirably adapted for repairs should any of the planks rot out or become broken or damaged. Since each plank is individually secured to both the hoops and the concrete retaining wall, it may be individually detached and replaced by a new plank. The nuts on the bolts 14 and 15 are all in the most easily accessible positions. Such breakage, however, or other damage to the planks is not liable to occur except through carelessness or accident. As a precautionary measure to facilitate the removal of a plank, it is advisable when erecting the silo to treat all bolts and nuts with tar, oil or other substances which will prevent rusting.

My initial and primary object is to provide a silo construction but it is obvious that the structural principles herein described are applicable to other storage containers. The structure would have identically the same advantages if it were used as a water tank as it has in its use as a silo. Wheat or other grains may be stored in the structure and the pressure of these grains is great enough to force the wedge strips 13 into tight relation in the notches at the joints between the planks 10. The height and diameter of the structure are governed entirely by the specific use to which the structure is to be put. In general, the diameter of the structure as a silo depends on the rate at which the silage is to be used while the height of the structure depends largely on the amount of silage required for the season's feeding. If the structure is to be used as a water tank, the quantity of water as well as the necessary pressure must be considered in determining the diameter and the height of the water tank.

Some farmers prefer what is commonly

called a trench silo, built horizontally on the ground. For such silos, vertical staves would be used with the same joint between planks and having all of the same general advantages inherent in the construction of the vertical silo as above described.

Having thus described my invention in such full, clear, and exact terms that its construction and operation will be readily understood by others skilled in the art to which it pertains, what I claim as new and desire to secure by Letters Patent of the United States is:

1. In a silo, a cylindrical body part comprising separate vertically disposed and spaced apart planks, hoops enclosing the planks to hold the same in circular order, said planks having beveled edges at their inner sides providing depressions at the adjacent edges of the planks, and wedge strips seated in the depressions adapted to be forced outwardly toward the beveled edges to seal the joints between the adjacent planks.

2. A silo, comprising an annular concrete retaining wall adapted to be embedded in the soil, a plurality of vertically positioned planks, fastening means for individually and releasably securing the lower ends of the planks to said retaining wall against the inner surface thereof, a plurality of hoops surrounding said silo and releasably secured to said planks, said planks being beveled on their inner edges to provide notches at the meeting edges thereof and wedge strips loosely secured to said hoops and seated within the notches between contiguous planks, said wedge strips being adapted to be forced by the pressure of the silage into intimate contact with the edges of said planks to close the joints therebetween.

In testimony whereof I affix my signature.
JAMES RUSSEL ROBERTS.
